UNITED STATES PATENT OFFICE.

EARL EDWARD HOFFMAN, OF SPRINGFIELD, MASSACHUSETTS, ASSIGNOR TO INDIAN MOTORCYCLE COMPANY, OF SPRINGFIELD, MASSACHUSETTS, A CORPORATION OF MASSACHUSETTS.

DISPLAY STAND FOR SUPPORTING TWO-WHEELED VEHICLES.

Application filed February 4, 1924. Serial No. 690,522.

To all whom it may concern:

Be it known that I, EARL EDWARD HOFFMAN, a citizen of the United States, residing at Springfield, in the county of Hampden, State of Massachusetts, have invented certain new and useful Improvements in Display Stands for Supporting Two-Wheeled Vehicles, of which the following is a description, reference being had to the accompanying drawing, and to the figures of reference marked thereon.

The invention relates to new and useful improvements in display stands for supporting two-wheeled vehicles such as motor cycles and the like.

An object of the invention is to provide a stand which will hold a two-wheeled vehicle in upright vertical position while the wheels thereof are on the ground or floor, which stand is capable of yielding so that the vehicle may be swayed sidewise, thereby giving something of the effect of riding so that the prospective purchaser is enabled to ascertain the riding quality and therewith be instructed in the control system while the vehicle is at a standstill.

A further object of the invention is to provide a stand of the above type with supporting rollers or wheels so that the vehicle can be readily moved laterally on the floor.

These and other objects will in part be obvious and will in part be hereinafter more fully disclosed.

In the drawings—

Fig. 1 is a view showing the attachment of the stand to a motorcycle frame.

Fig. 2 is a perspective view showing one embodiment of the invention.

Fig. 3 is a perspective view of the attaching member mounted on the cycle frame.

Fig. 4 is a perspective view showing an alternative form of the invention.

Fig. 5 is a detail view showing the connection of the resilient arm and its spring to the bracket.

My improved stand for supporting motor cycles or the like comprises broadly a device which is adapted to be attached to the frame of the vehicle and which has arms extending laterally therefrom, the ends of which arms are held in contact with the ground or floor by means of a spring or springs. The contact which the outer end

of each arm has with the ground or floor is preferably through rollers which are located so as to turn about axes parallel with the longitudinal center line of the vehicle. This stand is so formed and placed that when it is attached to the vehicle the ends of the lateral arms will bear on the ground or floor while the wheels of the vehicle are still on the ground or floor. This provides a means for holding the vehicle in upright vertical position. It also enables an operator to mount the vehicle and sway the machine from side to side without tipping over, as the resilient support of the lateral arms is sufficient to overcome the tendency of the vehicle to fall over.

Referring more in detail to the drawings, I have shown in Fig. 1 only a part of a motor cycle frame which is indicated by the frame parts 1, 1. My improved stand consists of a spring member 2 which is reinforced by a second shorter leaf member 3. These members are secured to a supporting bar 4 by means of a bolt 5 and by shackles 6, 6. The ends of the support 4 are bent upwardly as at 7, 7, and a bolt 8 passes through the ends of the upturned parts 7, 7 and also through sleeves 9, 9 permanently carried by the frame of the motor cycle or two-wheeled vehicle. This forms a rigid supporting means for the spring stand. On the one end of the leaf spring 2 there is a rod 10 which passes through the curled end of the spring, and on this rod are two wheels 11, 11. At the other end of the spring there is a rod 12 on which are two wheels 13, 13. The spring support is attached to the vehicle in such a way that when the vehicle stands on the floor or ground, the heft of the machine will rest on the ground. The wheels 11, 11 and 13, 13 however, which are carried by the laterally extending leaf spring will also rest upon the ground or floor and will operate to normally hold the vehicle in upright position. The spring 2 yields sufficiently to bring about this normal positioning of the parts. It will also be noted that a rider may mount the machine, and when on the machine, he may sway the machine from one side to the other, the spring 2 yielding for this purpose, and thus he gets something of the effect of riding. The spring is stiff enough however, to prevent the motor cycle from

falling over sidewise, and will return the same to upright position even with the person seated in the saddle.

In the form of invention shown in Fig. 2, the lateral arms are formed of inflexible material and are hinged to the bracket carried by the frame of the vehicle. The spring is so placed with relation to each arm that it forces the arm against the ground or floor thereby holding the vehicle in upright position.

Referring more in detail to Fig. 2 of the drawings, the frame 1, 1 just as in Fig. 1, is provided with sleeves 9', 9', to receive the bolt 8' of the bracket carried by the upright arms 7' of the support 4'. The two opposite ends of this support 4' are provided with lugs 5' on which are pivotally mounted as at 6', the lateral arms 2'. These lateral arms are formed with upward extensions 3' between which and the sides of the uprights 7' of the bracket are coiled the springs 14. As in Fig. 1, the extreme ends of the arms 2' are provided with the rollers 11. The location of this spring as before stated, operates to force the arm against the floor thereby holding the vehicle in upright position.

It is obvious that minor changes in the details of construction and arrangement of the parts may be made without departing from the spirit of the invention as set forth in the appended claims.

Having thus described the invention, what I claim as new and desire to secure by Letters-Patent, is—

1. A display stand for two-wheeled vehicles comprising supporting means, means for securing said supporting means to the frame of the vehicle with said supporting means extending laterally of the vehicle and supported on the floor at each side of the vehicle, said supporting means being constructed and arranged to resiliently support said vehicle in upright position.
2. A display stand for two-wheeled vehicles comprising a leaf spring member, means for rigidly securing said spring member to the vehicle frame so that said spring member extends laterally to each side of the vehicle frame and adapted to rest on the floor or ground and thereby holding the vehicle in

upright position, but permitting the rider on the seat of the vehicle to sway the vehicle to one side or the other without falling over sidewise.

3. A display stand for two-wheeled vehicles comprising a leaf spring extending laterally on opposite sides of the vehicle, a reinforcing spring for said leaf spring, a support to which said springs are secured, said support having upstanding members, and means for securing said upstanding members to the frame of the vehicle.

4. A display stand for two-wheeled vehicles comprising a leaf spring, bolts mounted in the ends of the springs, a pair of wheels on each bolt, a reinforcing spring engaging the leaf spring intermediate its ends, a support at the center of the reinforcing spring and leaf spring, a bolt and shackles for securing the springs to said support, said support having upstanding members, and means for securing said upstanding members to the vehicle frame.

5. A display stand for two-wheeled vehicles comprising a member rigidly attached to the frame of the vehicle, a device having laterally extending arms attached to such member, and means pressing each arm against the ground whereby said vehicle is held resiliently in upright position.

6. A display stand for two-wheeled vehicles comprising a bracket rigidly attached to the frame of the vehicle and carrying laterally extending arms, the outer ends of which rest upon the ground and being capable of movement in a vertical plane, and resilient means supported against the bracket for acting upon said arms to overcome the tendency of the vehicle to fall sidewise.

7. A display stand for a two-wheeled vehicle in which the latter has its wheels upon the common base, a bracket having laterally extending resiliently mounted arms attached to the frame of the vehicle, rollers in contact with the common base, and axle pins for said rollers carried at the ends of said arms and disposed at right angles to the rear axle of the vehicle.

In testimony whereof, I affix my signature.

EARL EDWARD HOFFMAN.
